FRANCIS M. BRINCKERHOFF, OF ENGLEWOOD, NEW JERSEY, ASSIGNOR TO FORSYTH BROTHERS COMPANY, OF CHICAGO, ILLINOIS, A CORPORATION OF ILLINOIS.

UNIT-SECTION SIDE FRAME FOR CARS.

1,090,594.

Specification of Letters Patent. Patented Mar. 17, 1914.

Application filed July 18, 1912. Serial No. 710,136.

To all whom it may concern:

Be it known that I, FRANCIS M. BRINCKERHOFF, a citizen of the United States, residing at Englewood, in the State of New Jersey, have invented certain new and useful Improvements in Unit-Section Side Frames for Cars, of which the following is a specification.

My invention relates to unit section side frames for steel cars and has for its primary object a simplification and consequent reduction of the cost of manufacture accompanied by an increased rigidity of the car structure and an improved finish doing away with overlapping riveted or welded joints and providing the window openings with integral pressed sash members or glass supporting flanges.

Having this general object in view the invention contemplates the construction of the side sheathing of a car from unit sections corresponding in individual extent to the window opening divisions longitudinally of the car and vertically extending the full height of the car side, the line of junction between the several sections being either along the medial vertical line of the side posts between the window opening or along the medial line of the window openings themselves. In either case the opening is defined by an integral flange inturned from the sheathing unit and the side post of the car is confined between the adjacent flanges of contiguous openings, the side post and flanges serving for mutual support and thus adding further rigidity to the structure as a whole.

In order that the structural features of the invention may be readily understood I have in the accompanying drawings illustrated the same as embodied in two slightly different forms.

In these drawings, Figure 1, is a side elevation of a car side showing an I-shaped unit section; Fig. 2, is a vertical section on the line 2-2 of Fig. 1; Fig. 3, is a detail section upon an enlarged scale on the line 3-3 of Fig. 1; Fig. 4, is a view similar to Fig. 1, but illustrating a rectangular unit section; Fig. 5, is a vertical section on the line 5-5 of Fig. 4; and Fig. 6 is a horizontal section on the line 6-6 of Fig. 4.

In these drawings and having particular reference to Figs. 1, 2 and 3, the side sheathing of the car is shown as made up of I-

shaped unit sections which for convenience may be designated as comprising each a lower portion 11 below the belt rail of the car, a panel portion 12 extending vertically between the window openings and a letter-board portion 13 above the window openings. In this form of construction each of the units is of a general I-shape and embraces vertically the full height of the car and longitudinally the adjacent halves of two window openings 14, 14.

The rectangular sheet of metal from which the sheathing unit is to be made is by a press provided upon opposite edges in those portions corresponding to the adjacent halves of the window openings with a depression in the shape of a panel of which the lower portion is off set in a plane parallel to the general plane of the sheet. The offset portion is then punched out at a slight distance from its edge so as to leave an opening having a margin. It will thus be seen that the unit section provides on opposite edges adjacent halves of two contiguous window openings defined by the inturned continuous flange 15 and the offset continuous flange 16 extending across the bottom of the opening to form a sill and along the side and over the top of the opening to form the casing. It will also be seen that when the car side is built up of unit sections joined by welding or in other suitable manner along the vertical line corresponding to the medial line of the opening, the entire window opening is defined by the inturned continuous flange 15 and the offset continuous marginal flange 16.

The marginal flange 16 may serve as a sash member or support for the glass 17. A packing strip 18 of rubber, felt or the like is arranged between the edge of the glass 17 and the flange 16 while a filler block 19 of substantially the width of the glass and packing strip surrounds the outer edge of the glass and rests upon the flange 16. A glazing strip 20 overlies the packing strips 18 and the filler block 19 in opposition to the offset flange 16 and is clamped upon the packing strip and filler block by means of clamping screws made up of male and female members 21 and 22 having a countersunk bearing upon the glazing strip and the flange respectively. By this means the glass is held firmly in position and the entrance of dust or moisture effectually precluded while

the glass is easily removed for renewal in case of damage.

The sheathing units are secured by riveting or in other approved manner to the side sill 23 and the side plate 24 and also to the side posts 25 which latter occupy a position immediately to the rear of the panel portion 12 of the sheathing and are of such width as to snugly fit within the space between the 10 adjacent flanges 15 of contiguous window openings 14. In this way the flanges 15 of the sheathing coöperate with the posts 25 to mutually support each other and contribute to increase the rigidity and strength of the 15 structure as an entirety.

The embodiment shown in Figs. 4, 5 and 6 differs from that already described in that, instead of the sheathing units being of a general I-shape and each embracing the half of 20 contiguous window openings, they are of general rectangular shape joined along the medial vertical line of the side post and each embraces an entire window opening. In this 25 form of construction the rectangular sheet of metal is in its upper central portion formed with a depressed panel and the offset panel is punched out along its top and side edges and at a distance from its bottom edge so as to provide along the top and sides the 30 inturned flange 27 and to leave an offset bottom portion 28, the upper margin of which portion 28 is then bent inwardly to form a horizontal sill 29.

The several sections are arranged with 35 their meeting edges abutting along the medial line of the side post 30 which post, as in the form of construction previously described, is of a width to fit snugly between the flanges 27 of contiguous window openings. The sheathing units are as in the former case suitably secured to the side posts and above and below to the side plate 31 and side sill 32, the flanges 27 of the sheathing units and the side post 30 mutually supporting 40 each other to lend additional rigidity to the construction and forming together a very efficient side frame. The window openings in this form of construction are adapted to receive window sash of any approved form 45 and to be fitted with sash guides for the retention and operation of the sash.

It will be obvious to those skilled in the art that the invention may be embodied in other forms of construction than those illustrated without departing from the legitimate scope thereof wherefore I do not wish to be understood as limiting myself to the particular construction shown.

I claim:

60 1. In a side frame for cars, the combination of a series of sheathing units providing window openings, the sheathing flanged inwardly at the sides of the openings, and side posts interposed between and bearing 65 against the adjacent flanges of contiguous

openings, the sheathing units secured to the side posts, substantially as described.

2. In a side frame for cars, the combination of a series of sheathing units providing window openings, the sheathing flanged inwardly around the entire opening and side posts interposed between and bearing against the adjacent flanges of contiguous openings, the sheathing units secured to the side posts, substantially as described. 75

3. In a side frame for cars, the combination of a metallic sheathing providing window openings, the sheathing flanged inwardly around the openings, and side posts interposed between and bearing against the adjacent flanges of contiguous openings, substantially as described. 80

4. In a side frame for cars, the combination of a series of sheathing units providing window openings, the sheathing flanged inwardly to form a continuous flange surrounding the openings, and side posts interposed between and bearing against the adjacent flanges of contiguous openings, the sheathing units secured to the side posts and 85 above and below to the side plate and side sill of the car, substantially as described. 90

5. In a side frame for cars, the combination of a metallic sheathing providing window openings, said sheathing flanged inwardly at substantially right angles around 95 the window opening and then offset in a plane parallel to the general plane of the sheathing, and reinforcing members interposed between the flanges of adjacent openings, substantially as described. 100

6. In a side frame for cars, the combination of a metallic sheathing providing window openings, said sheathing flanged inwardly at substantially right angles around 105 the window opening and then offset in a plane parallel to the general plane of the sheathing, and side posts interposed between and bearing against the adjacent flanges of contiguous openings, the sheathing secured 110 to the side posts, substantially as described.

7. In a side frame for cars, the combination of a metallic sheathing providing window openings, said sheathing flanged inwardly at substantially right angles around 115 the window openings and then offset in a plane parallel to the general plane of the sheathing, the sheathing further flanged at the bottom of the opening at an angle to the offset portion, and reinforcing members interposed between and bearing against the bottom flanges of adjacent openings, substantially as described. 120

8. In a side frame for cars, the combination of a metallic sheathing providing 125 window openings, said sheathing flanged inwardly at substantially right angles around the top and sides of the opening and also flanged inwardly at the bottom of the opening to a distance beyond the side and top 130

flange and reinforcing members interposed between and bearing against the bottom flanges of adjacent openings, substantially as described.

5. 9. In a side frame for cars, the combination of a series of sheathing units providing window openings, the sheathing flanged inwardly at the sides of the openings, and side posts housed within the space between and 10 engaging the adjacent flanges of contiguous openings, the sheathing units secured to the side posts, substantially as described.

10. In a side frame for cars, the combination of a metallic sheathing providing 15 window openings, the sheathing flanged inwardly at the bottom of the openings, and reinforcing members interposed between and bearing against the ends of the bottom flanges of contiguous openings, substantially 20 as described.

11. In a side frame for cars, the combination of a metallic sheathing providing window openings, said sheathing flanged inwardly at substantially right angles at the 25 side of the window openings and then offset in a plane parallel to the general plane of the sheathing, and reinforcing members interposed between and engaging the flanges of adjacent openings, substantially as de- 30 scribed.

12. In a unit side frame construction, the combination with a side sill and side plate, of a pressed steel unit having a lower widened portion rigidly secured to the side 35 sill and a vertical stem secured to and supporting the side plate, the widened portions of adjacent units disposed beneath the window openings, and the stems separating the window openings, substantially as described.

40 13. In a unit side frame construction, the combination with a side sill and side plate, of a pressed steel unit having a lower widened portion rigidly secured to the side sill and a vertical stem rigidly secured to 45 and supporting the side plate, the widened portions of adjacent units disposed beneath the window openings and the stem separating the window openings, whereby the lower widened portions take the shear load 50 and the bending moment is sustained at the junction of the widened portion and stem coinciding substantially with the window sill, substantially as described.

14. In a unit side frame construction, the 55 combination with a side sill and side plate, of a pressed steel sheathing unit having a lower widened portion rigidly secured to the side sill and a vertical stem rigidly secured to and supporting the side plate, the 60 widened portions of adjacent units united together beneath the medial vertical line of

the window openings and the stem separating the window openings, the margins of the widened portions and stem inwardly flanged to form a window sill and side 65 finish, substantially as described.

15. In a unit side frame construction, the combination with a side sill and side plate, of a pressed steel unit of substantially I-shape having its lower horizontal portion 70 rigidly secured to the side sill and its upper portion rigidly secured to and supporting the side plate, the widened portions extending beneath and above the window openings and the stem portion separating the window 75 openings, the margins of the widened portions and stem inwardly flanged and offset to form a window sill and casing finish, substantially as described.

16. In a unit side frame construction, the 80 combination with a side sill and side plate, of a pressed steel unit having a stem arranged to take the load from the side plate and a lower wider horizontal portion projecting beneath the window openings and 85 transmitting the load to the side sill, substantially as described.

17. In a unit side frame construction, the combination with a side sill and side plate, of a pressed steel sheathing unit having a 90 lower widened portion rigidly secured to the side sill and a vertical stem rigidly secured to and supporting the side plate, the widened portions of adjacent units united together beneath the medial vertical line of 95 the window openings and the stem separating the window openings, the margins of the widened portions and stem inwardly flanged to form a window sill and side 100 finish, and posts housed within the space between the flanges of the stem, substantially as described.

18. In a unit side frame construction, the combination with a side sill and side plate, of a pressed steel sheathing unit having a 105 lower widened portion rigidly secured to the side sill and a vertical stem rigidly secured to and supporting the side plate, the widened portions of adjacent units united together beneath the medial vertical line of 110 the window openings and the stem separating the window openings, the margins of the widened portions and stem inwardly flanged to form a window sill and side 115 finish, and posts housed within the space between the flanges of the stem and bearing against said flanges, substantially as described.
